MUSIC LEAF TURNER

William L. Wilkinson, Kalamazoo, Mich.

Application October 26, 1938, Serial No. 237,137

3 Claims. (Cl. 84—486)

My invention relates to the handling of sheet music, and has among its objects and advantages the provision of an improved music leaf turner.

An object of my invention is to provide a music leaf turner embodying novel means for quickly and accurately turning the pages of the sheet music in such a manner as to eliminate the necessity for having to take the individual sheets between the fingers for turning purposes. The 10 turner embodies novel means for handling sheet music of different sizes and is so constructed as to effectively turn individual sheets or pages of a book. The turning mechanism is incorporated in a frame structure which may be folded back 15 upon the sheets or bound volume in the manner of a book cover so as to provide a compact unit for handling purposes in addition to affording protection for the music.

In the accompanying drawings:

- 20 Figure 1 is a plan view of my invention;
- Figure 2 is an enlarged sectional view along the line 2—2 of Figure 1;
- Figure 3 is a sectional view along the line 3—3 of Figure 1;
- 25 Figure 4 is a sectional view along the line 4—4 of Figure 1;
- Figure 5 is a side elevational view showing the unit folded in combination with a clamp for supporting the unit;
- 30 Figure 6 is an end view;
- Figure 7 is a detail view of a portion of the clamp structure;
- Figure 8 is a sectional view along the line 8—8 of Figure 7;
- 35 Figure 9 is a perspective view of a portion of the mount for the turner; and
- Figure 10 is a perspective view of the standard associated with the part illustrated in Figure 9.

In the embodiment selected to illustrate my 40 invention, Figure 1 illustrates the music turner open for supporting the sheet music. The frame units 10 are identical in construction, each comprising side bars 12 and 14, end cross bars 16 and 18, and intermediate cross bars 20. All the cross 45 bars 16, 18 and 20 have their ends arranged in overlapping relation with the side bars 12 and 14 and are fixedly related thereto, as by rivets 22. A latch bar 24 is associated with each of the frames 10, and each latch bar is arranged in 50 parallel relation with its respective side bars 12 and 14, centrally of its respective frame. Latch bars 24 are riveted to the end bars 16 and 18, as at 26.

Referring to Figures 1 and 2, the side bars 14 55 are hingedly connected with a center column 28,

so that the frames 10 may be folded to the position of Figure 6, at which time the frames and the columns define a configuration simulating the covers of a book, for housing the sheet music therebetween.

Column 28 comprises a metal strap 30 of a length slightly longer than the side bars 14. Spacers 32 extend longitudinally of the bottom face of the strap 30 for supporting a second strap 34 in spaced relation with the strap 30. Straps 10 30 and 34 and the spacer 32 are connected into unitary structure by screws 36.

Hinges 38 are attached to the side bars 14 and the strap 30 by screws 40. The axes of the hinges 38 are located directly over the meeting line between the side bars 14 and the edges of the strap 30. Figure 2 illustrates the frames 10 opened, at which time the adjoining edges of the side bars 14 have abutting relation with the edges of the strap 30 to support the frames 10 in a common 20 plane with the strap 30.

Between the spacers 32 and the straps 30 and 34, I mount a plurality of wires 42 which are curved at their lower ends, as at 44, to provide grips facilitating rotation of the wires. The upper ends of the wires 42 are provided with right angular arms 46 of lengths substantially equal to the width of one frame 10. The right angular arms 46 are doubled back upon themselves at 48 to provide right angular extensions which stack 30 one upon the other when arranged according to Figure 1. Similarly, the outer ends of the arms 46 are bent to provide cross extensions 50 which also stack one upon the other. Extensions 48 and 50 constitute abutments which cooperate with 35 each other for preventing the arms 46 from assuming a disorderly arrangement should the arms 46 be offset or shifted slightly laterally of one another.

Upon each arm 46 I mount a pair of V-shaped 40 links 52 each having its ends looped at 54 about its respective arm 46. To the bight of each link 52 is connected a conventional spring clip 56. Each arm 46 carries two links 52 so that each sheet of music connected with one of the arms 45 46 will have two clip connections. The links 52 are slidably related to their respective arms 46 so that the clips 56 may be adjusted to sheets or pages of variable sizes. One sheet is connected with each of the arms 46.

In operation, the sheets are connected with the arms 46, and lie on the right hand frame 10 when viewing Figure 1. The sheets are turned over from the right hand frame 10 onto the left hand frame 10. In cases where the music is in book 50 55

form, the book is positioned with its back positioned along the column 28. The slideable connection between the links 52 and their respective arms 46 permit effective turning of bound sheets 5 even though the bound volume is not accurately aligned with the center column 28.

In use, the frames 10 are positioned substantially in an upright position, as indicated by the angularity of the center column 28 in Figure 5. 10 The weight of bound volumes may be supported on a rest 58, extending transversely of the frames, see Figure 1. Rest 58 comprises straps 60 lying flat upon the latch bars 24 and transversely of the same. Straps 60 are provided with right angular flanges 62 which carry the weight of the music. The inner ends of the straps 60 are connected with a plate 64, through the medium of hinges 66 having their axes aligned with the axes of the hinges 38. Plate 64 is provided with a 15 right angular flange 68 and the plate is slideable freely relatively to the center column 28.

Each latch bar 24 is provided with a plurality of closely spaced perforations 70, and each flange 62 is provided with a pin 72 arranged to project 25 through selected perforations in its respective latch bar 24 to permit the rest 58 to be latched in different positions of adjustment longitudinally of the latch bars 24 so as to accommodate music of different lengths. Each strap 60 is provided 30 with a loop 74 which extends underneath its respective latch bar 24 for holding the rest 58 in assembled relation with the latch bar. Loops 74 are loosely related to the latch bars 24 so as to permit the rest 58 to be elevated sufficiently far 35 to bring the pins 72 out of holding relation with the perforations 70. Thus the rest 58 may easily be moved upwardly or downwardly of the frames 10.

In Figures 2, 5 and 6, I illustrate the strap 34 40 of the center column 28 as being provided with a loop 76 into which the end 78 of a standard 80 may be detachably inserted. End 78 is bent at an angle to the standard so as to hold the center column 28 in the angular position of Figure 5, 45 with the standard 80 positioned substantially vertically. The lower end of the standard 80 is provided with an end 82 shaped for removable insertion in a loop 84 fixedly related to a supporting bar 86. 50 The ends of the bar 86 are positioned inside the U-bend 88 of clamp parts 90. Each clamp part 90 carries a screw 92 extending through a slot 94 in a companion clamp bar 96 having a hook 98. Companion clamp bar 96 includes an angular 55 reach 100 having a threaded opening 102 for the reception of an adjusting screw 104 extending loosely through an opening 106 in the flange 108 of the clamp part 90. Screw 104 includes a flange 110 bearing against the flange 108 and is provided 60 with a knurled knob 112 to facilitate turning. Hooks 98 cooperate with the U-bends 80 to the end that the parts might be clamped to a supporting structure (not shown.)

Latch bars 24 have their ends curved upwardly, 65 at 114 when viewing Figure 1. The latch bars 24 extend beyond the cross bar 16 so as to afford rests for the arms 46 in either position. Standard 80 is detachably connected with the center 70 column 28 as well as with the bar 86. At the same time, the bar 86 is detachably connected with the U-bends 88. Thus the parts may be disconnected for packaging purposes so as to provide a compact arrangement facilitating transportation and 75 movement from place to place.

Figure 6 illustrates the manner in which the device may be folded in the manner of a book. A U-shaped clip 116 is arranged to be pressed over the side bars 12 for holding the frames 10 in the position of Figure 6 with the sheet music or book 5 clamped between the frames 10. With the device folded according to Figure 6, the reaches of the latch bars 24 extending beyond the cross bars 16 and 18 afford protection for the frames 10 and the music associated therewith when the device is 10 placed in a container or package. Wires 44, while being centrally housed in the manner of Figure 2, rotate easily, while the grips 44 provide effective means for selectively turning the wires, which in turn turns the sheets 116 connected with the 15 clip 56. Rest 58 folds with the frames 10 so as to be housed inside the frames.

Without further elaboration, the foregoing will so fully illustrate my invention that others may, by applying current knowledge, readily adapt the 20 same for use under various conditions of service.

I claim:

1. A music leaf turner comprising two frames, a column having a hinge connection with each frame to connect the frames and the column in 25 the form of a book cover with the frames comprising the sides of the cover and the column the back thereof, said column being relatively wide with respect to its thickness and having a relatively wide by narrow opening extending longitudinally therethrough with the opening having its wide extent arranged widthwise of the width of said column, a plurality of wires extending longitudinally through said opening and each having a right-angular leaf turning arm, said wires lying 30 loosely in juxtaposed relation in said opening in a plane widthwise of said opening, and said wires contacting one with the other and with the walls of said opening to be confined in said juxtaposed relation but with each wire rotatably independent 40 of the other wires.

2. A music leaf turner comprising two frames, a column having a hinge connection with each frame to connect the frames and the column in 45 the form of a book cover with the frames comprising the sides of the cover and the column the back thereof, said column being relatively wide with respect to its thickness and having a relatively wide by narrow opening extending longitudinally therethrough with the opening having 50 its wide extent arranged widthwise of the width of said column, a plurality of wires extending longitudinally through said opening and each having a right-angular leaf turning arm, said wires lying loosely in juxtaposed relation in said opening in a plane widthwise of said opening, said wires contacting one with the other and with the walls of said opening to be confined in 55 said juxtaposed relation but with each wire rotatably independent of the other wires, said right-angular leaf turning arms pivoting in a common plane about the axes of their respective wires, and bends in said right-angular leaf turning arms arranged to rest one upon the other to prevent 60 tangling thereof.

3. A music leaf turner comprising two frames, a column having a hinge connection with each frame to connect the frames and the column in 70 the form of a book cover with the frames comprising the sides of the cover and the column the back thereof, said column being relatively wide with respect to its thickness and having a relatively wide by narrow opening extending longitudinally therethrough with the opening having 75

its wide extent arranged widthwise of the width of said column, a plurality of wires extending longitudinally through said opening and each having a right-angular leaf turning arm, said wires 5 lying loosely in juxtaposed relation in said opening in a plane widthwise of said opening, said wires contacting one with the other and with the walls of said opening to be confined in said juxtaposed relation but with each wire rotatably independent of the other wires, said right-angular leaf turning arms pivoting in a common plane about the axes of their respective wires, bends in 10 said right-angular leaf turning arms arranged to rest one upon the other to prevent tangling thereof, said frames being pivotal to closed positions, grip formations on said wires lying beyond one end of said column and the corresponding ends of said frames, said right-angular leaf turning arms lying beyond the opposite end of the column and the corresponding ends of said frames, and projections carried by said frames for engaging a container to protect said grip formations and the right-angular leaf turning arms from engagement with the case, with certain of said projections comprising rests for said right-angular leaf turning arms. 10

WILLIAM L. WILKINSON.
